UNITED STATES PATENT OFFICE.

GYURO E. B. JAKOPETS, OF CHICAGO, ILLINOIS

PERMUTATION-PADLOCK.

1,259,519.

Specification of Letters Patent. Patented Mar. 19, 1918.

Application filed July 9, 1917. Serial No. 179,434.

To all whom it may concern:

Be it known that I, GYURO E. B. JAKOPETS, a subject of the Emperor of Austria, residing at Chicago, in the county of Cook and State of Illinois, have invented certain new and useful Improvements in Permutation-Padlocks, of which the following is a specification.

This invention relates to new and useful improvements in permutation pad-locks.

The primary object of the invention is the provision of a permutation pad-lock possessing great strength and adapted for operation in connection with permutation members, the structure being easy and inexpensive to manufacture.

The further object of the device is to provide a permutation pad-lock having a separable shackle the same being maintained in its locked position when desired by means of a plurality of permutation members reusable by a person who is familiar with the combination thereof.

A still further object of the invention is the provision of a permutation pad-lock which cannot be "picked" nor released by an unauthorized person, the same requiring a knowledge of the combination of permutation members with which the same is provided in order to unlock the device.

In the drawing forming a part of this application and in which like reference characters designate corresponding parts throughout the several views,

Fig. 1 is an elevational view of the device partially broken away illustrated in its locked arrangement.

Fig. 2 is a sectional view taken upon line II-II of Fig. 1.

Fig. 3 is a top plan view of the device partly broken away.

Fig. 4 is a detail perspective view of the main shaft member of the lock and a portion of the shackle support.

Fig. 5 is a similar perspective view of the bolt member of the device and

Figs. 6 and 7 are end views of the two different forms of permutation members employed with the device.

Referring more in detail to the drawing a shaft 10 is provided centrally projecting from a circular disk or head 11 formed at one end of the device upon one arm 12 of a shackle section 13. A similar head 14 normally maintained opposite the head 11 is provided with a bolt 15 rectangular in cross

section and adapted for slidable reception within a longitudinal side-slot 16 of the shaft 10.

The head 14 is carried by an arm 17 having a shackle section 18 at its opposite end, both of the shackle sections 13 and 18 being substantially U-shaped and forming the receiving opening 19 of the lock when the bolt 15 is operatively positioned within the slot 16 and with the free end 20 of the bolt in substantial engagement centrally with the head 11.

The shackle section 13 has its opposite sides 21 provided with sockets 22 adapted for the reception of dowel pins 23 carried by the opposite sides 24 of the shackle section 18. A plurality of permutation members 25 and a slightly different single permutation member 26 are journaled upon the shaft 10 and are provided with desirable characters such as the letters 27 herein shown, which by means of the arrangement herein-after set forth control the locking and unlocking of the device during the action of a predetermined turning of the permutation members.

Radially projecting lugs 28 are suitably positioned opposite each other upon the shaft 10 while similar lugs 29 are provided upon the bolt 15 adapted to project radially from the shaft 10 when the bolt is seated within the slot 16 and at which time it will be noted the lugs 28 and 29 are arranged in the same diametrical planes of the shaft 10.

Each of the permutation members 25 and 26 is of cylindrical construction, being internally chambered, and having centrally positioned openings 30 whereby the same may be journaled upon the shaft 10 when the bolt 15 is seated within the slot 16. Opposite radial slots 31 and 32 are provided in the opposite sides of the members 25 adapted for permitting the members 25 to be moved over the lugs 28, receiving the said lugs 28 within the members 25. The slots 32 of the members 25 and 26 are of greater width than the slots 31 whereby the members 25 and 26 may be turned upon the shaft 10 bringing the slots 32 into alignment with the slot 16 of the shaft and thereby permitting the free longitudinal movement of the bolt 15 outwardly and inwardly of and within the slot 16. It is noted that the lugs 29 of the bolt 15 are of greater dimensions than the lugs 28 carried by the shaft 10, the lugs 29 being adapted for pas-

sage through the slots 32 of the permutation members 25 and 26, but being incapable of passing through the slots 31 thereof.

The permutation member 26 is arranged with both of the slots 31 and 32 upon its inner side but is only provided with the wider slot 32 upon its outer side which is normally in engagement with the shackle head 14. It will be seen that the three members 25 and the end member 26 may be readily positioned upon the shaft 10 when the bolt 15 is removed while the slots 32 may then be positioned in alinement with the slot 16 permitting the insertion of the bolt 15 within the slot 16 bringing the dowels 23 within the sockets 22 and the shackle in its closed operative position. By turning the members 25 and 26 in any direction, the combination will be broken and the bolt 15 will be locked by the permutation members against being withdrawn. Upon again setting the combination, the slots 32 of all of the permutation members 25 and 26 will be again brought into alinement with each other outwardly of the slot 16 permitting the withdrawal of the bolt 15 and the free passage of the lugs 29 of the bolt 15 through the said slots 32. It is obvious that any desirable characters 27 may be employed with any of the same arranged outwardly of the slots 32 and when the same are arranged in a straight line and in line with such an indicia as the points 33 upon the heads 11 and 14, the combination will be in its releasing position for permitting the same movement of the bolt 15.

The complete operation of the device will be apparent from this detailed description thereof it being seen that a permutation pad-lock is arranged giving great security and which is easily operable by a person familiar therewith.

What I claim is:—

1. A lock comprising co-operating shackle members provided with heads, a slotted-shaft carried by one of said heads, a bolt carried by the other head adapted for reception within the slot of said shaft, lugs

disposed on opposite sides of said slotted shaft, lugs on the bolt of greater dimensions than the lugs on the shaft and arranged to lie in the same transverse plane as the slotted-shaft lugs when the bolt and shaft are in assembled position, a plurality of ring-like permutation members having laterally centrally apertured annular chambers, said permutation members being mounted on the shaft for rotation thereon with the lugs of the bolt and the lugs of the shaft positioned within the permutation members when in locked position, said permutation members having radial side slots of greater dimensions than the lugs of the bolt and adapted to engage the bolt lugs outwardly of the shaft slot when the shackle members are in unlocked position.

2. A lock of the type described, including co-operating shackle-members having interfitting socket and dowel connection, and adapted to form a keeper for the reception of the lock-attaching means, said shackle-members being provided with circular heads, one of said shackle-members being provided with a slotted shaft having lugs on the opposite sides thereof and the other shackle-member being provided with a bolt received by the slot of said shaft, said bolt having lugs of greater dimensions than the lugs on the shaft and arranged to lie in the same transverse plane as the shaft lugs when the members of the lock are assembled, a plurality of ring-like permutation members having laterally centrally apertured annular chambers, said permutation members being mounted on the shaft for rotation thereon, with the lugs of said bolt and shaft positioned within the permutation members when in locked position, said permutation members having radial side slots of greater dimensions than the lugs of said bolt and adapted to engage said bolt lugs outwardly of the shaft-slot when the device is in its unlocked position.

In testimony whereof I affix my signature.

GYURO E. B. JAKOPETS.
